[57] CLAIM

The ornamental design for a bottle for perfume, as shown and described.

DESCRIPTION

FIG. 1 is a perspective view of a bottle for perfume showing my new design;

FIG. 2 is a top plan view thereof;

FIG. 3 is a front elevational view thereof, the rear view thereof being a mirror image of FIG. 3;

FIG. 4 is a side elevational view, the opposite side being the same in appearance; and

FIG. 5 is a bottom plan view thereof.
